STORAGE RACK FOR A TABLE TENNIS SET

Frank E. Shock, 1563 NE. Parkway, Wichita, Kans.

Filed Dec. 5, 1960, Ser. No. 63,107

Term of patent 14 years

(Cl. D33—3)

The drawing is a perspective view of a storage rack for a table tennis set showing my new design.

The back of the rack is plain and unornamented.

I claim:

The ornamental design for a storage rack for a table tennis set, as shown, and described.
